UNITED STATES PATENT OFFICE.

WILLIAM C. NORCROSS, OF TERRE HAUTE, INDIANA.

COMBINATION JOLT-RAMMING AND ROCK-OVER MACHINE.

1,245,955.

Specification of Letters Patent. Patented Nov. 6, 1917.

Application filed December 21, 1916. Serial No. 138,204.

To all whom it may concern:

Be it known that I, WILLIAM C. NORCROSS, a citizen of the United States, residing at Terre Haute, county of Vigo, and State of Indiana, have invented certain new and useful Improvements in Combination Jolt-Ramming and Rock-Over Machines, of which the following is a specification.

This invention relates to combination jolt-ramming and rock-over machines.

Machines of the general class to which my invention belongs embody an automatic jolt-ramming machine, a supplemental table to support the flask and mold, and means for swinging or rocking the supplemental table over, after the mold has been rammed, to bring it to an inverted position, so that the mold may be drawn or lowered away from the pattern. Machines of this general character are exemplified in the construction set forth in my Patent No. 1224407 dated May 1, 1917.

My object is to provide in the present invention novel means for rocking the supplemental table over into inverted position, which embodies a construction of extreme simplicity, great strength and durability, positiveness of action and adaptability to accomplish rocking-over of the table, in an automatic manner, by elevation and depression of the piston of the jolt-ramming machine, under the control of a suitable valve. Furthermore, the novel rock-over mechanism set forth hereinafter is adapted for use in connection with a movable drawing table or with a stationary table, the rock-over mechanism serving either purpose, according to the type of drawing table employed.

The present improvements embody novel lever mechanism of a minimum number of parts, co-operatively related to the supplemental rock-over table in such manner that the foregoing operations may be carried out with either a stationary or a movable drawing table.

Another object of the invention is the provision of a drawing table having adjustable flask or mold supports whereby a shorter drawing cylinder may be employed and the effective movement of the table minimized when drawing a very shallow flask.

If desired a cushioning device such as a spring or an oil cushion mechanism may be used in connection with the rock-over mechanism to eliminate or substantially minimize the jerk, if any, of the rock-over table as it approaches vertical position. Furthermore,

I may use a spring mechanism which will not only accomplish the foregoing function but will assist in returning the rock-over table to normal position after the mold has been drawn.

I may also provide a cushion spring co-operating with the rock-over mechanism to prevent shearing off of the pivots when the mold is being rammed.

The embodiment of the invention herein-after set forth and shown in the accompanying drawings should be considered as illustrative, rather than restrictive, of the scope of the invention as modifications may be resorted to without departing from the principle thereof.

In the accompanying drawings,

Figure 1 is a side elevation, partly in section, the parts being shown in full lines in normal position and the lever mechanism straightened out and locked in dotted lines to illustrate the elevation of the mold to the first position prior to drop of the piston;

Fig. 2 is a similar view illustrating by dotted lines the second step where the piston has lowered to swing the supplemental table and the mold into vertical position, full lines representing the third, or rock-over, position, the piston being then elevated;

Fig. 3 a side elevation showing the fourth position wherein the lever mechanism is unlocked so that the piston may be again lowered to permit the mold to be lowered onto a stationary leveling table;

Fig. 4 a detail view of the improved drawing table of Figs. 1 and 2; and

Fig. 5 a detail view showing a cushion spring to prevent shearing off of the pivots.

While the present improvements are shown and described in connection with certain features of the jolt-ramming machine of my Patents, 1,194,059, August 8, 1916, and No. 1224407 May 1, 1917, they are not to be considered as limited to that particular machine, as they may be used on other jolt-ramming machines. The improvements in the drawing table are shown and described in connection with the leveling device of my application, Serial No. 126,845, filed October 21, 1916, but they are not limited to use in connection therewith.

The machine has a base 1 which supports cylinder 2, having a valve controlled inlet pipe 3 and a valve controlled exhaust pipe 4. In the cylinder is a piston 5, which carries the main table 6 and the supplemental or rock-over table 7, which is hinged thereto at 8.

To admit the motive fluid pressure to the bottom of the cylinder 2 beneath the lower end of the piston 5, there is provided a pipe 9, having a three-way valve 10. The valve 10 remains closed during the ramming of the mold, the valves of the pipes 3 and 4 then being open. When the mold has been rammed, the valves in the pipes 3 and 4 are closed, so that the piston is then subject to pressure entering through the pipe 9 or exhausting through said pipe, according to the manipulation of the valve 10. By manipulating the valve 10, the operator can elevate the piston 5 or lower it as desired, to thereby bring about the different positions of the lever mechanism and the supplemental and main tables, to cause rocking-over of the mold and the return of the supplemental table.

The piston head may be guided by bolts 11 and the fit between the piston head and the table 6 may be a driving fit. The valve mechanism, not shown, may be that disclosed in my patents aforesaid. A stop bolt 11^a limits the upward movement of the table 6.

The supplemental or rock-over table 7 has a lug 12 provided with an adjustable stop screw or bolt 13 adapted to bear against the table 6 when the table 7 is in inverted position, as shown in Figs. 2 and 3 by full lines, to thereby form an abutment for the supplemental table.

One or two of the rock-over mechanisms now described may be employed, but only one need be used. Pivoted at 14 is the lower link 15 of a lever mechanism whose upper link 16 is of bell crank form, the two links being pivoted together at 17 and one of them having a stop or lug 18 to engage the other of them when they are in alined condition so that they are in position to be secured together by any suitable locking device 19, which can be manipulated by hand, such as a bolt on link 15 adapted to enter a hole (Figs. 1, 3, 5) in link 16. The upper end of the bell crank link 16 is pivoted at 20 to the supplemental table 7. Normally, during the reciprocations of the piston 5 when the mold is being rammed, the lever mechanism turns on the pivots 14, 17, 20, and the table 7 rests on the table 6. The parts are then in the position shown by full lines in Fig. 1.

After the mold has been rammed, the valves in the pipes 3 and 4 are closed and the rocking over of the table 7 with the flask, mold, and pattern carried thereby, is accomplished by manipulation of the three-way valve 10. Air is let into the bottom of the cylinder 2 until the tables and parts assume the positions shown by dotted lines in Fig. 1. Table 7 is then on the table 6 and the links 15, 16 have straightened out into alignment and are locked by the locking device 19, so that the lever 15, 16, is rigid throughout, and will thereafter rock on its pivot 14 alone until the lock 19 is released. The operator next turns the valve 10 to exhaust the pressure beneath the piston 5, whereupon the piston and the table 6 lower but this action causes the table 7 to be rocked by the lever 15, 16, to the vertical dotted line position of Fig. 2, the table 6 being then in the lowered dotted line position. The operator again turns the valve 10 to admit pressure beneath the piston 5, whereupon the latter again rises and assumes the full line position of Fig. 2, but as the table 7 is pivoted at 8 to the table 6, the table 7 is rocked over to the inverted, full line, position of Fig. 2. The stop 13 now abuts the table 6. The mold is then ready to be drawn from the pattern, the latter remaining connected to the table 7. A reversal of the foregoing operations will rock the table 7 back to the raised dotted line position of Fig. 1. The lock 19 must then be released so that the links 15, 16, can turn on the pivot 17, whereupon the table 7 may be lowered, with table 6, to the full line position of Fig. 1.

Assuming that the table 7 is in the rocked-over or inverted position shown by full lines in Fig. 2, the lock 19 then holds the links 15, 16, rigid with each other. If the lock 19 be released when the lever is in this position, the piston 5 may be lowered by exhausting the pressure through the valve 10, the links 15, 16 then bending on the pivot 17. The table 7 in its inverted position will then lower, together with the table 6 and piston 5. This construction enables a stationary drawing table or mold support 21, Fig. 3, to be used. Such a table should have some leveling means so that it will adapt itself to the bottom board or battens of the mold-flask 22. The particular advantage of this adaptability of the lever mechanism 15, 16, is that the necessity of employing a raising and lowering drawing table with a cylinder and piston is obviated. In the operation shown in Fig. 3, once the flask 22 has become supported by the stationary table 21, surmounting column 21^a, and the flask and mold have been released by hand from the table 7, they remain on the stationary table 21, the pressure can be admitted into the bottom of cylinder 2, thereby elevating the table 6 and with it the table 7, resulting in straightening out of the links 15, 16, until they come into line and are locked as shown in full lines in Fig. 2. Return of the inverted table 7 to normal position, in the manner heretofore described, may then be had.

The operation just described is not necessary when a drawing table which raises and lowers as in Figs. 1, 2 is employed.

In Figs. 1, 2 and 4, there is shown a draw-

ing cylinder 23 having a piston, not shown, which supports a table 24. The table illustrated is that shown in my application Serial No. 126,845, with improvements applied, 5 consisting of mold supports 25 adapted to be raised and lowered, and held where adjusted. These supports are located at the end portions of the sections 26 of the table 24, and are carried by stems 27 which are adjustable vertically in the split ends 28, and 10 are held by bolts 29, which clamp the split ends against said stems 27. The supports 25 can be raised to any desired height to approximate the position of the bottom board 15 of the mold flask 22, so that the play of the piston in the cylinder 23 and the extent of elevation of the table 24 need be only very short to accommodate the supports to the depth of the flask. The sections 26 are self-leveling, as they bear upon the ball end 30 20 of the piston and are articulated by bolt 31, as in my aforesaid application.

An oil cushion such as set forth and described in my Patent No. 1224407, may be applied to the lever 15 to cushion the jerk, if any, as the table approaches vertical position, but I do not limit myself to the use of this device.

As shown in Fig. 5, I may use a balancing 30 spring 32 coöperating with the link 16, to accomplish the same purpose and to assist in returning the table 7 to its normal position on its return from inverted position.

There may also be employed, if desired, 35 a cushion, or shock-absorbing, spring 33 supported by base 1 at 34 and having its upper end provided with a head 35 on which lever 15 rests. This serves to prevent shearing action on the pivots 14, 17, 20, particularly 14 40 and 17, when the piston 5 is reciprocating during the ramming of the mold.

The table 6 may be dispensed with and the table 7 directly hinged to the head or end of piston 5. I do not, therefore, limit myself 45 to the use of table 6. The effect of hinging table 7 to table 6 is the same as hinging table 7 directly to piston 5.

Having thus described my invention, what I claim as new and desire to secure by 50 Letters Patent is:

1. A combination jolt-ramming and rock-over machine comprising a piston and cylinder, valve controlled means for admitting and exhausting motive fluid pressure thereto, 55 to elevate and lower the piston, a rock-over table carried by the piston, and means co-operating with the rock-over table adapted to cause rocking-over of said table by three or more successively different and alternately opposite movements of said piston.

2. A combination jolt-ramming and rock-

over machine comprising a piston and cylinder, valve controlled means for admitting and exhausting motive fluid pressure thereto to elevate and lower the piston, a rock-over 65 table carried by the piston, an articulated lever mechanism coöperating with the rock-over table, and means for releasably locking the parts of said lever mechanism so that they may be rigid, or movable, in relation 70 to each other, said lever mechanism being adapted to cause rocking-over of the table.

3. In a mechanical movement, the combination with a movable carrier, of a rock-over table carried thereby, and an articulated 75 lever comprising links directly jointed together, one part having a pivotal connection with said table distinct from the pivot of the latter, the other part having a fixed pivot, said lever being adapted to cause the 80 table to rock over when the carrier is moved.

4. In a mechanical movement, the combination with a movable carrier, of a rock-over table carried thereby, an articulated lever having a pivotal connection with said 85 table, and means for releasably locking the parts of the articulated lever together.

5. In a mechanical movement, the combination with two tables adapted for disposition in superposed relation, of a pivotal connection between said tables, means for raising and lowering said tables as a unit, an articulated lever having one of its parts pivoted to one of said tables and another of its parts pivotally mounted, and a releasable 90 locking device whereby the parts of the articulated lever may be secured together in rigid relationship to effect swinging of the table to which the lever is pivoted.

6. In a mechanical movement, the combination with a movable carrier, of a rock-over table carried thereby, and means co-operating with the rock-over table adapted to cause rocking-over of said table by three or more successively different and alternately opposite movements of said movable 105 carrier.

7. A combination jolt-ramming and rock-over machine comprising a piston and cylinder, valve controlled means for admitting and exhausting motive fluid pressure thereto to elevate and lower the piston, a rock-over table carried by the piston, a sectional lever mechanism coöperating with the rock-over table, and means for releasably locking the 110 sections of said lever mechanism so that they may be rigid, or movable, in relation to each other, said lever mechanism being adapted to cause rocking over of the table.

In testimony whereof, I hereunto affix my 120 signature.

WILLIAM C. NORCROSS.
